UNITED STATES PATENT OFFICE.

ELEAZER KEMPSHALL, OF NEW BRITAIN, CONNECTICUT.

SNAP-HOOK.

SPECIFICATION forming part of Letters Patent No. 257,721, dated May 9, 1882.

Application filed December 15, 1881. (No model.)

To all whom it may concern:

Be it known that I, ELEAZER KEMPSHALL, of New Britain, in the county of Hartford and State of Connecticut, have invented certain new and useful Improvements in Snap-Hooks, of which the following is a specification:

My invention relates to improvements in snap-hooks of the class which have a longitudinally-sliding bolt, in which the cylindrical hollow body of the hooks is made in two semi-cylindrical halves, with lugs upon one half, which take into recesses in the other half; also, in which a cylindrical body is provided with a hook and longitudinally-sliding bolt at each end, with a single spring between acting upon both bolts; and the objects of my improvements are, first, to reduce the cost of construction, and, second, to produce a double snap-hook which shall be compact in form, and which can be made at a small cost. I attain these objects by the simple construction shown in the accompanying drawings, in which—

Figure 1 is a side elevation of the two halves of the body in the form in which they are cast. Figs. 2 and 3 are plan views of one of said parts. Fig. 4 is a central longitudinal section of the complete snap, partly in elevation. Figs. 5 and 6 are transverse sections of the body on line $\alpha\alpha$ of Figs. 4 and 8, showing respectively the two halves before and after securing them together. Fig. 7 is a plan view, showing my two-part body applied to a single instead of a double hooked snap; and Fig. 8 is a side elevation of the same.

A designates the lower, and B the upper, half of the cylindrical body, both of which are substantially in the form of a semi-cylindrical shell in cross-section for the greater portion of their length.

The part A has a hook, a , at each end. As in ordinary snaps, these hooks are first cast as bent off to one side, after which they are straightened into the position shown in Figs. 4, 7, and 8.

Side recesses, b , are cast in the part A, and corresponding lugs, c , are cast on the part B, the same being formed preferably of cast malleable iron. The part B might, however, be readily formed of sheet metal. The bottoms of the recesses b slant inward toward each other, as shown in Figs. 5 and 6.

The parts are placed together with the lugs on part B entering the recesses in part A, as shown in Fig. 5, after which the lugs are bent inward, as shown in Fig. 6, to hold the two parts of the body together. The seams are filled up, and the parts also further secured together during the usual tinning operation. No drilling is required to make room for the spring and sliding bolts.

After one of the sliding bolts d has been inserted the hook for that end may be bent into position. Then insert the spring and the other bolt and bend the other hook into position, and the device is complete. The same spring acts upon both sliding bolts, and therefore the body of this double-hooked snap does not have to be made twice the length of a single one. Such double-hooked snaps are useful upon breast-straps, and in many other places.

Figs. 7 and 8 show the first part of my invention as applied to a single-hooked snap, and the same reference-letters are used to designate corresponding parts, but have the character ' affixed thereto.

I do not claim a snap-hook having a cylindrical body with spring and a longitudinally-moving bolt working therein, as the same is old; neither do I claim a double-hooked snap, because a prior patent shows a snap with a hook at each end, and a single piece of sheet metal extending from hook to hook, fastened at the middle of its length to the body of said hook, so that each end constituted a spring-tongue adapted to close its own hook.

I claim as my invention—

1. In a snap-hook, the cylindrical body consisting of two semi-cylindrical shells having lugs upon one part and corresponding recesses in the other part, which hold the parts together when the lugs are put in place and bent inward, substantially as described, and for the purpose specified.

2. The improved double-hooked snap, consisting of the cylindrical body, two hooks and sliding bolts, and one spring acting upon both sliding bolts, substantially as described, and for the purpose specified.

ELEAZER KEMPSHALL.
